UNITED STATES PATENT OFFICE.

PEARL M. SRADER, OF LEBANON, KANSAS.

CIRCULAR EXTENSION-TABLE.

1,226,134.

Specification of Letters Patent. Patented May 15, 1917.

Application filed November 15, 1915. Serial No. 61,618.

To all whom it may concern:

Be it known that I, PEARL M. SRADER, a citizen of the United States, residing at Lebanon, in the county of Smith, State of Kansas, have invented certain new and useful Improvements in Circular Extension-Tables; and I do hereby declare the following to be a full, clear, and exact description of the invention, such as will enable others skilled in the art to which it appertains to make and use the same.

The present invention is directed to improvements in circular extension tables, and has for its object to so construct a device of this character that the same can be easily and quickly extended when desired.

A further object of the invention is to provide a table of this character with a supplemental rotary table adapted to receive food, the same being so mounted that it can be conveniently rotated by a diner so as to place the desired food into position to be conveniently reached.

With these and other objects in view, this invention resides in the novel features of construction, formation, combination and arrangement of parts to be hereinafter more fully described, claimed and illustrated in the accompanying drawing, in which:

Figure 1 is a top plan view of the table, showing the extension segments in place.

Fig. 2 is a top plan view of the main table, the rotary table being removed.

Fig. 3 is a sectional view on the line 3—3 of Fig. 1.

Fig. 4 is a fragmentary bottom plan view of the main table, showing the extension sections in place.

Fig. 5 is a fragmentary bottom plan view of the rotary table.

Fig. 6 is a sectional view on the line 6—6 of Fig. 5.

Fig. 7 is a side elevation of the complete table.

Fig. 8 is a detail sectional view of the ball race.

Referring to the drawing, 1 indicates the pedestal, which has suitably attached thereto supporting legs 2, said pedestal also having suitably connected to its lower end a circular block 3. The block 3 and legs 2 are each provided with suitable casters, whereby the table can be rolled from place to place.

The main table 4 comprises a circular top 5, connected to the upper end of the pedestal

1, and provided adjacent its outer edge with a depending flange 6, provided with a plurality of pairs of spaced openings 7. Located adjacent each opening 7 is a socket 8, the purpose of which will later appear.

A plurality of segment-shaped extension sections 9 are provided, each of which is provided with a pair of spaced arms 10 inserted in the openings 7 so that their inner ends will engage in the sockets 8, whereby the sections 9 are held in firm horizontal position with their adjacent ends in abutting relation. Thus it will be seen that the sections 9 can be easily and quickly removed from engagement with the top 5 or engaged therewith as desired.

The upper surface of the top 5 has suitably connected centrally thereof a sheet metal circular plate 11 provided with an up-standing circular flange 12, spaced from the edge of the plate 11. The edge of the plate 11 has a marginal flange 13 which forms in conjunction with the flange 12 a race-way 14 for receiving the ball bearings 15, the purpose of which will appear later.

The rotary table 16 comprises a circular top 17 which has fixed to its under surface a circular plate 18, having a vertical marginal flange 19 which encircles the flange 13 so that the plates 11 and 18 are held against relative lateral movement. The top 17 is provided adjacent its edge with a flange 20, said flange being also provided with openings 21 and sockets 22 which are adapted to receive the arms 23 carried by the segment-shaped extension sections 24. Thus it will be seen that the rotary table can be extended when desired.

To facilitate the rotation of the top 17 the flange 20 thereof is provided with a plurality of handles 25, similar handles 26 being carried by the sections 24.

The respective extension sections 9 and 24 are retained in their operative positions by the hooks 27 and 28.

What I claim is:

An extension table comprising a supporting pedestal, a main table supported by the pedestal and comprising a top having a depending circular flange provided with openings therein, means for forming sockets interiorly of said flange and in registration with said openings, extension sections having arms the inner ends of which detachably engage said openings in the sockets, a rotary table top having extension sections detach-

ably connected thereto, a circular plate fixed to the upper surface of the first named top, spaced concentric flanges carried by said plate for forming a raceway, ball bearings 5 in said raceway, and a circular plate carried by the second named top and engaging the balls in said raceway and having a depending flange engaging the outer surface of the

outer concentric flange of the first named plate.

In testimony whereof, I affix my signature, in the presence of two witnesses.

PEARL M. SRADER.
